6 Claims. (Cl. 235—60)

This invention relates to calculating machines having a setting pin carriage.

In the last few years, attempts have been made to increase the speed of calculating machines more and more. In the course of experiments aimed at increasing machine speed a plurality of new problems such as rebounding calculating means and machine noise have been encountered.

The object of the invention is to provide a solution of one such problem in calculating machines having a machine frame, a setting pin carriage, setting pins on said carriage, supporting means supporting said carriage on said machine frame for reciprocation in a first direction, and transmitting means on said machine frame movable in a sensing course into bearing engagement with said setting pins in a second direction substantially at right angles to said first direction. In such a calculating machine the invention provides resilient means forming part of said supporting means and allowing said carriage to move yieldingly in relation to said machine frame out of a position of rest approximately in said second direction.

Further objects and features of as well as the advantages gained by the invention will appear from the following description, reference being had to the accompanying drawing diagrammatically illustrating two embodiments of the invention.

Fig. 1 is a plan view, partly in section, of the mechanism according to the invention;

Fig. 2 is a view of the mechanism in Fig. 1 as seen from the right, one frame end wall being partly broken away;

Fig. 3 is a view similar to Fig. 1 of another embodiment of the invention.

With reference to Fig. 1, two side walls 1 and 2 and a front wall 3 are shown of the frame of a calculating machine. Extending between the side walls 1, 2 and in parallel with the front wall 3, is a rod 4 on which a setting pin carriage 5 of prior art construction is movably mounted by means of lugs 6. In the usual manner, the carriage 5 has a plurality of setting pins 7 arranged in mutually perpendicular rows. Some of said setting pins 7 only are shown in the drawing for the sake of clarity. In the normal position of the machine in which the keyboard of the machine is zero set, the carriage 5 occupies a starting position adjacent a stop 8 connected with the rod 4. When numbers are entered on the machine keyboard (not shown), the setting pin carriage 5 is displaced through one step to the left as seen in Fig. 1 along the rod 4 for each digit entered, and during this stepwise movement row after row of setting pins will be placed in the path of movement of a plurality of transmitting means 9, only one of which is shown in the drawing for the sake of clarity. For each digit key depressed a setting pin 7 in one of the carriage setting pin rows perpendicular to the rod 4 is raised in the usual manner which is not therefore shown in detail. The transmitting means 9 shown in the drawing is in the form of a rod mounted in a

2

known manner on the machine frame so as to be movable approximately in parallel with the upper side of the carriage 5 and at right angles to the rod 4 in the direction indicated by the arrow 10 in Fig. 2. Said rod 9 has a 5 downwardly directed projection 11 which during the sensing course of the rod effected in the direction of the arrow 10 meets the setting pin 7 raised by the digit key, thus being stopped by said setting pin whereby calculating means (not shown) of a known type are set for the value 10 corresponding to that of the digit key depressed. After the digits entered on the carriage 5 have been transmitted by the transmitting means 9 in this way, the carriage 5 is returned by elements not shown to its starting position in which it is in bearing engagement with the stop 8.

The rod 4 is mounted in the following manner to permit rapid operation of the machine without the risk that the transmitting means 9 will rebound to a detrimental extent against the setting pins 7 and that the carriage 5 will rebound against the stop 8 at its return movement so that 15 calculating errors and noise arise. The ends of the rod 4 extend through slots 12 in the frame end walls 1, 2. Said slots 12 are elongate in a direction parallel to that of direction 10, and they guide the rod in such a way that it is movable on one hand in its longitudinal direction 20 and on the other at right angles to its longitudinal axis approximately in the direction 10 of the sensing course of the transmitting means 9, while at the same time, as indicated in Fig. 2, they limit the vertical movement of rod 4, and prevent it from moving substantially in a vertical direction, i.e. in a direction perpendicular both to the axis of rod 4 and to the direction 10 of the sensing course of transmitting means 9. In unactuated condition the rod 4 is held in a normal position by resiliently yielding means. On each end of the rod 4 outside the 25 respective frame end walls 1, 2 there are rotatively mounted two adjacent arms 13, 14 and 15, 16, respectively. The said arms are plate-shaped. In each arm pair one arm has a projection 17 at the upper end while the other arm has a projection 18 at the lower free end, and these two 30 projections are interconnected by means of a pull spring 19 interposed between them. Besides, each of the arms has a hole 20 by means of which they are passed onto the respective end of a rod 21 secured in the frame end walls 1, 2. The hole 20 in each arm 13 to 16 is substantially 35 square, except for one corner of the square which is cut away by an edge 22 making an angle of approximately 45° with the adjacent square sides and merging with the adjacent square sides approximately at the middle of the length that these sides would have if they were the sides 40 of a real square. The opposite and mutually parallel sides of the hole 20 are spaced a somewhat greater distance apart than the diameter of the rod 21. The edge of each hole 20 which is remote from the rod 4 is approximately at right angles to the connecting line between the axes of the rods 4 and 21, and the oblique edge 22 of each hole faces away from the rod 4 and is situated on the same side of said connecting line as the projection 45 17 and 18, respectively, of the respective arms 13 to 16. The spring 19 urges the oblique edges 22 into engagement 50 with the rod 21 whereby a component thrust arises which is directed away from the rod 4 along the connecting line between the axes of the rods 4 and 21 and which thus results in a displacement of the rod 4 together with arms 13 to 16 to the left as seen in Fig. 2, the side edges of the 55 holes 20 remote from the rod 4 being pressed against the rod 21 which is stationary in relation to the frame end walls 1, 2. In the position of rest of the machine, the rod 4 is therefore held at a determined distance from the rod 21 in a normal position. When the projections 60 11 of the transmitting means 9 meet setting pins 7 on the carriage 5 during their sensing courses, there arises a 65 70

shock which is taken up resiliently and softly without any appreciable rebound of the transmitting means 9 against the setting pins 7 by the rod 4 and the arms 13-16 moving rearwardly while the oblique edges 22 of the openings 20 slide against the stationary rod 21 and move the arm projections 17, 18 apart against the action of the spring 19 which immediately after the shock returns the projections 17, 18 to their original spaced apart position, while the oblique hole edges 22 slide back against the rod 21 so that the rod 4 and thereby the carriage 5 are returned to a predetermined position of rest which is defined by the lateral hole edges remote from the rod 4 bearing against the rod 21 under the action of the springs 19. The movement of the rod 4 towards the rod 21 under the action of the shocks of the transmitting means 9 are restricted to a certain maximum in that the vertical edges of holes 20 closest to the rod 4 will bear against the rod 21 during the movement of the rod 4 and thus of the arms 13-16 towards said rod 21, whereby said edges constitute stops for limiting the movement of the rod 4 out of the position of rest towards the rod 21.

Experiments have shown that to obtain the best possible damping of the shocks of the transmitting means 9 against the setting pins 7 without any appreciable rebound and noise, the left-hand spring 19, as seen in Fig. 1, should be stronger than the right-hand one. The reason for this construction is that the shock energy to be absorbed varies from one computation to another in accordance with the number of setting pins raised (the number of shocks by transmitting means 9 abutting against raised setting pins during the sensing course), the number of simultaneous impacts between raised setting pins and transmitting means and to a certain extent also the distance that the transmitting means have to move to abut the raised setting pins. A low shock energy is best damped by a weak spring action and a high shock energy demands a strong spring action. When the shock energy is low the shock is damped substantially only by yielding of the weak right-hand spring 19 in Fig. 1 so that in a broad sense the rod 4 is fulcrumed about its left-hand end support formed by the arms 13, 14 gripping the rod by means of the strong left-hand spring 19, which will not yield or yield only to a small extent. When the shock energy is high the shock is damped partly by complete yielding of the weak right-hand spring 19 in Fig. 1 until the left-hand vertical edges of the openings 20 in the arms 15, 16 in Fig. 2 abut against the rod 21 and partly by yielding of the strong left-hand spring 19 in Fig. 1.

The arms 15, 16 are disposed on the righthand end of the rod 4, as seen in Fig. 1, between a locking plate 23 and a rubber disk 24. The locking plate 23 is inserted in a groove at the end of the rod 4. The stop 8 is in the form of a sleeve and loosely passed onto the rod 4. It has a flange 25 which is in bearing engagement with the face of the rubber disk 24 facing away from the arms 15, 16. A further rubber disk 26 is interposed between the flange 25 and the frame end wall 2. The arms 13, 14 at the left-hand end of the rod 4, as seen in Fig. 1, are mounted on said rod between a locking plate 27, inserted in a groove at the rod end, and a cup-shaped rubber buffer 28 which is applied with its cup edge against the frame end wall 1 and which, in the position of rest of the machine, holds the assembly formed by parts 8, 15, 16, 23-26 snugly moved together with the rubber disk 26 bearing against the frame end wall 2 so that the rod 4 and the stop 8 are held in a definite position of rest longitudinally of the rod 4. When the carriage 5 is returned to its starting position by means of the prior art elements (not shown) after the transmitting means 9 have performed their sensing course, the carriage 5 meets the stop 8, the resulting shock being resiliently taken up without any appreciable rebound and noise in that the stop 8 resiliently yields to the carriage 5 arriving in starting position, because said stop can move to the right as

seen in Fig. 1 while carrying the rod 4 along and compressing the rubber buffer 28.

Another way of realizing the inventive idea is shown in Fig. 3. The rod 4 is here immovably secured in the end walls of the machine frame, of which the end wall 2 only is shown in Fig. 3. The lugs 6 of the carriage 5 have holes 29 through which the rod 4 extends and which in the direction 10 of the sensing course of the transmitting means 9 has a larger extension that the rod 4 whereby the carriage is movable in relation to the rod approximately in the direction 10 of the sensing course of the transmitting means 9 as well as in the opposite direction. Bores 30 are provided in the lugs 6. Said bores are at right angles to the rod 4 and open into the holes 29. Balls 31 are inserted in said bores 30 and are held pressed against the rod 4 by springs 32 in said bores 30 so that the carriage 5 in a position of rest is held resiliently displaced by the springs 32 as far as possible in a direction opposed to the direction 10, the portion of the wall of the holes 29, which is opposed to the bores 30, bearing against the rod 4. When the transmitting means 9 perform their sensing course in the direction 10 and meet the adjusted setting pins 7 of the carriage 5, the shock is resiliently and softly taken up by the carriage being displaced approximately in the direction 10 in respect of the stationary rod 4, while the balls 31 are pushed into the bores 30 and the springs 32 are compressed, which springs after the shock return the carriage to the position of rest shown in Fig. 3.

Pistons may be substituted for the balls 31. It is also possible to substitute a leaf spring or the like for each spring mechanism 30-32, which leaf spring is secured to the carriage and resiliently bears against the rod. The means, e.g., lugs 6, by which the carriage 5 is mounted on the rod 4, can also be mounted in their entirety on the carriage in such a way as to be resiliently movable with respect to the carriage approximately in the direction 10 and in the opposite direction. The spring mechanism 30-32 arranged in connection with one mounting means 6 may have a steeper spring characteristic than the other mechanism, in analogy with what has been described for the spring mechanisms of the rod 4 in the embodiment according to Figs. 1 and 2.

In the embodiment according to Fig. 3, the frame end wall 2 proper constitutes the stop for arresting the carriage 5 during its return movement to the right as seen in Fig. 3. The right-hand lateral edge of the carriage 5 has a bore 33 accommodating a spring 34 which tends to push a piston 35 out of the bore into a position of rest in which it bears against a stop (not shown) in the bore and in which the right-hand end of the piston projects from the carriage side face so that during its return movement the carriage will hit the end wall 2 with the piston 35. As a result, said piston is pushed into the bore 33, compressing the spring 34 and resiliently damping the shock against the end wall 2. After the shock action has ceased, the spring 34 returns the piston 35 to its position of rest so that the carriage 5 will occupy a predetermined starting position in respect of the longitudinal direction of the rod 4. It is obvious that instead of the spring-actuated piston 35 it is possible to arrange some other kind of a spring buffer on the carriage 5 for damping the shock of the carriage against the end wall 2 during the return movement of the carriage.

While the invention has been described in the foregoing in two embodiments thereof, it must not be regarded as restricted thereto, for many modifications may be resorted to within the scope of the invention, such as is defined in the appendant claims, as will readily be realized by those skilled in the art. It should be observed especially that it is possible to use in one and the same machine both the embodiment according to Figs. 1 and 2 and the one according to Fig. 3.

What we claim and desire to secure by Letters Patent is:

1. In a calculating machine a machine frame, a setting pin carriage, setting pins on said carriage, supporting means supporting said carriage on said machine frame for reciprocation in a first direction, transmitting means on said machine frame movable in a sensing course into bearing engagement with said setting pins in a second direction substantially at right angles to said first direction, guide means allowing substantial movement of said carriage in said second direction and preventing substantial movement thereof in a direction perpendicular to said first and second directions, and resilient means acting on said carriage in a direction opposite and parallel to said second direction and urging it to a position of rest.

2. In a calculating machine frame, a rod mounted in said frame, a setting pin carriage mounted on said rod for reciprocation therealong parallel to a first axis which is the longitudinal axis of said rod, parallel setting pins mounted in said carriage for reciprocation parallel to a second axis, said second axis being parallel to the longitudinal axes of said setting pins and perpendicular to said first axis, transmitting means mounted on said frame for reciprocation parallel to a third axis which is perpendicular to said first and second axes, said transmitting means being movable in a sensing direction parallel to said third axis and into bearing engagement with said setting pins, rod guide means in said frame allowing substantial movement of said rod in a direction parallel to said third axis and preventing substantial movement of said rod in a direction parallel to said second axis, and resilient means acting on said rod in a direction parallel to said third axis, urging said rod to a position of rest.

3. In a calculating machine a machine frame, a rod, first and second rod mounting means at the respective opposite ends of said rod mounting said rod in said frame, a setting pin carriage mounted on said rod for reciprocation therealong parallel to a first axis which is the longitudinal axis of said rod, parallel setting pins mounted in said carriage for reciprocation parallel to a second axis, said second axis being parallel to the longitudinal axes of said setting pins and perpendicular to said first axis, transmitting means mounted on said frame for reciprocation parallel to a third axis which is perpendicular to said first and second axes, said

transmitting means being movable in a sensing direction parallel to said third axis and into bearing engagement with said setting pins, first and second rod guide means in said frame adjacent respectively to said first and second rod mounting means, each said rod guide means allowing substantial movement of said rod in a direction parallel to said third axis and preventing substantial movement of said rod in a direction parallel to said second axis, and first and second resilient means, each comprising respectively a portion of said first and second rod mounting means, each said resilient means acting on said rod in a direction parallel to said third axis and urging said rod into a position of rest.

4. A calculating machine as defined by claim 3, said first and second resilient means being of substantially different strengths, whereby each acts on said rod with a substantially different force.

5. A calculating machine as defined by claim 3, one end of said rod comprising a first member, a second member rigidly fixed to said frame, said second member being spaced from said first axis, one of said resilient means comprising a pair of plate members pivotally attached to one of said first and second members, a cam surface on each of said plate member, each cam surface facing the other one of said first and second members and being on the opposite side of a line joining the centers of said first and second members, and spring means urging said plate members to swing toward each other about said one of said first and second members to press said cam surfaces against said other one of said first and second members and thereby urge said rod toward a position of rest.

6. In a calculating machine as defined by claim 5, said one of said first and second members being said one end of said rod.
